STRAP TENSIONING AND SEALING DEVICE

Xaver Kuoni, Zurich, Switzerland

Application February 27, 1946, Serial No. 650,650
In Switzerland September 19, 1945

6 Claims. (Cl. 81—9.1)

1

The present invention relates to a tensioning and closing device for band iron hoops with a cutter head capable of being raised and lowered at right angles to the band, which head serves for guiding the band, closing the hoop and for cutting off the band.

According to the invention at least one cutter is arranged adjustable to various band widths in the cutter head, so that one and the same device can be used directly for different band widths. In a preferred form of the invention a number of cutters, provided with inclined cutting edges, are provided, which notch the band ends and a closing sleeve, and according to a further feature of the invention each cutter is provided with a plurality of pairs of cutting edges, so that by adjusting the cutters, for example by turning the same, the apparatus can be adjusted in a minimum period of time to different customary band widths.

The invention, furthermore, aims to provide a device of the mentioned type with a base plate, the front portion of which is curved in planes transverse in relation to the band portion engaged by the device during its operation, the curvature being such that the tension of the band will tend to tilt the device so as to facilitate its removal after the completion of its operation. Retractable means may be provided to prevent the tilting when it is not desired.

The accompanying drawing shows, by way of example, an embodiment of the invention, in its preferred form. In the drawing,

Fig. 1 is a front elevation.

Fig. 2 is a plan and

Fig. 3 is an end view of the device.

Fig. 4 is a section on the line IV—IV of Fig. 1.

Fig. 5 is a section on the line V—V of Fig. 4.

Fig. 6 is a section on the line VI—VI of Fig. 2.

Fig. 7 is a section on the line VII—VII of Fig. 2.

Fig. 8 is a section on the line VIII—VIII of Fig. 1.

Fig. 9 is a section on the line IX—IX of Fig. 1.

Fig. 10 is a front elevation similar to Fig. 1, with a band inserted in the device for tightening and closing.

The illustrated device comprises a frame 1 including a base plate 101, two parallel upright longitudinal walls 102 and 103 and two side walls 104 and 105. Only wall 103 rises from the base plate. The front wall 102 is located forward of the plate, whereas wall 103 is at a distance rearward of the front edge 2 of the plate. The wall 102 and the side walls 104 and 105 which connect walls 102 and 103 do not reach downward as far

2

as the baseplate 101. On the other hand, walls 102 and 103 extend upwards beyond the walls 104 and 105 whereas walls 104 and 105 extend farther downward than wall 102. In the zone where the four walls connect one another, they form a tubular housing 3 of rectangular cross-section which is open at both ends but overlapped at the bottom by the front portion 106 of the base plate 101. In this front portion, i. e. forward of wall 103, the total length of the otherwise plane lower side of the base plate is curved or rounded upwards to the raised front edge 2 so that the whole frame when resting on its base can be tilted forward in a rolling motion. In the housing 3, a cutter head 4 is vertically movable. In the latter a shaft 5 is journaled on which two cutters 6, 7 are provided with recesses 8, 9, 10 forming pairs of cutting edges 8', 9', and 10', respectively. The cutters 6, 7 are splined to the shaft 5 and are thus connected non-rotatably thereto. The end of the shaft 5 projects through a slot 11 in the housing wall 104 and carries a setting head 12, above which is arranged a stationary mark 13. In the cutter head 4, a roller 14 and a hook-shaped pawl 15 are mounted on a shaft 16. An eccentric 17 of an eccentric lever 18 cooperates with roller 14 and is provided with a pin 19 which can be engaged by the pawl 15 as shown in Fig. 5. A spring 20 tends to hold the pawl 15 hooked on the pin 19. The lever 18 is rockably mounted on a shaft 21, journaled in housing 3 and is provided with an extension 22 which in combination with an adjustable screw 23 serves as a stop for the lever. On the shaft 21 is seated a compression spring 25 which presses the eccentric 17 of the lever 18 against an abutment 26. Between the latter and the cutter head 4 a comparatively strong spring 27 is located which tends to press the head 4 downwardly. In a recess of the cutter head 4, there is also mounted a cutter blade 30 (Fig. 5) which serves to cut off the steel band which is to be closed by means of the device. The cutter blade is held in this recess by shaft 5 which is rotatable in a bore of the blade. Underneath the cutters 6, 7 grooves 31 are provided in the base plate 101 for the reception of the cutters 6, 7.

In two bearings 33, 34 of the base plate 101, an eccentrically hollow shaft 35 is journaled which carries a hand-lever 36, a control cam 37 (Fig. 7) and a pin 38 (Fig. 6). The pin 37 projects into a recess 40 of a horizontal shiftably and rockably mounted control rail 42 subjected to the action of a tension spring 41. The cam 37 co-operates with a control bolt 44 (Figs. 6, 9) which is sub-

jected to the action of a compression spring 45 and is provided with a reduced portion 46. The one end of the bolt 44 engages in a bore in the wall of bearing 34, whilst the other end projects beyond the bearing 33 (Fig. 9). The cam 37 is provided with a nose 48 (Fig. 7) which bears against the arm 49 of a two armed lever 50 pivoted on the base plate 101 at 150. The other arm 51 of the lever projects into a slot 53 of a bolt 55. Bolt 55 has a lower surface flush with the plane portion of the bottom surface of base plate 101 and is guided in a groove or recess 56 at right angles to the longitudinal edge 2. A spring 57, engaging with the arm 51, tends to hold the bolt 55 always in the position shown in Figs. 8 and 9, i. e. in the position extending as far as the edge 2. The control rail 42 is provided with an end 42¹ (Figs. 3 and 5) bent around the corner of the housing 3, which end carries a pin 58 adapted to engage an arm 15¹ of the pawl 15.

In the hollow shaft 35, an inner shaft 60 is mounted for free rotation, of which one end carries a tensioning roller 61 and the other end a ratchet wheel 62 with which engages a pawl 63. The latter allows the shaft 60 only to turn in one direction. The forked end of a hand lever 64 is also mounted on shaft 60 so as to rock freely thereon. This lever carries another pawl 65 engaging with the teeth of the ratchet wheel 62, which pawl is spring-biased and turns the ratchet wheel only in one direction.

In tensioning and closing a band iron hoop the device operates as follows:

The device is so placed on the article denoted by 70 in Fig. 10 and which is to be provided with a metal band 71, that it rests on the flat bottom portion of the base plate 101 and on the projecting bolt 55 which prevents the device from tilting. A closure sleeve 72 of a type conventional for the purpose is slid on the band which comes from a supply reel not shown. The free end 73 of the band is run around the article and passed through the sleeve a short distance so as to lie underneath the portion coming from the reel. The sleeve with the doubled band therein is placed in the device on top of the base plate so that the free end 73 is in the position shown on the left hand side of Fig. 10, the sleeve 72 underneath the cutters 6, 7, and the band portions adjacent the sleeve underneath the walls 104 and 105. Towards the right hand side, the doubled band extends underneath the tensioning roller 61. If the band is correctly inserted its edge pushes the control bolt 44 inwardly so that its reduced portion 46 coming to lie under cam 37 of the hollow shaft 35 permits turning of the control lever 36.

In order to guide the band in the device and to hold the sleeve firmly, the lever 36 is turned in the direction of the arrow I (Fig. 1) so that the pin 38 (Fig. 6) moves the control rail 42 until the pin 58 thereof engages the arm 15¹ of the pawl 15, and rocks the latter, whereby the nose of pawl 15 slides off the pin 19 (Fig. 5). The cutter head is now free and is pressed downwardly by the spring 27 so that the cutters 6, 7 bear upon the sleeve and firmly hold the band. Further movement of the control lever 36 in the same direction will cause the pin 38 to slide from the hook-shaped end of control rail 42 so that the latter will be restored to its original position by means of spring 41. Owing to the eccentricity of the bore of shaft 35 of lever 36, turning of the lever also lowers the inner shaft 60 so that the tensioning roller 61 will be pressed on the band

71. Thereupon the tensioning lever 64 will be raised and lowered a number of times, whereby with the aid of pawl 65, the ratchet wheel 62, the shaft 60 and the tensioning roller 61 are turned in a counter-clockwise direction in Fig. 10, and the band will be pulled tightly by the roller 61 around the article to be hooped. In the tightened condition the band has the tendency to tilt the device about the curved front portion of the base plate, which however, is not possible, by reason of the bolt 55 projecting forward of and flush with the plane bottom portion of the base plate, and having the effect of a foot in the range of the curved bottom portion. When the band is tight, cutter-head lever 18 may be rocked in the direction of the arrow II in Fig. 10. The eccentric 17 of the lever, through the roller 14, presses the cutter head 4 firmly downwardly, whereby its cutters 6, 7 notch the sleeve and the band, whilst the cutter 30 cuts the upper band part leading to the supply roll to such an extent that the band can be broken away easily by hand.

On restoring lever 18 to its original position the pin 19 thereof, engages the pawl 15, and raises the cutter head 46 into its upper position. Thereupon the control lever 36 is rocked opposite the direction of the arrow I so that the tensioning roller will be lifted and that the nose 48 engaging arm 49 will turn lever 50 so as to withdraw, with its arm 51, bolt 55 from its projected position. The tautly tensioned band is now capable of tilting the device about the curved front portion 103 of the base plate so that it can be removed with ease from under the band.

In order to enable bands of different widths to be used the cutters 6, 7 are provided with a plurality of recesses 8, 9, 10 of different widths with cutting edges 8', 9', and 10' respectively. By turning the knob 12 recesses corresponding with the band width to be used are adjustable in the lower, i. e. downward position.

It has been found of advantage to restrict the turning movement of the shaft 5 so that the shaft is rotatably mounted only in one direction so as to prevent the cutters 6, 7 from being turned accidentally under the influence of the tensioned or the tensioning metal band. It is thus advantageous to so mount the shaft 5 rotatably that the cutters 6, 7 cannot turn in a clockwise direction under the influence of the metal band (Fig. 4). Any suitable means may be applied for such purpose, e. g. a pawl and ratchet wheel of the type shown in Fig. 2 and denoted by 63 and 62 respectively. With reference to Fig. 4, the shaft 5 would thus be mounted rotatably solely in a counter-clockwise direction.

What I claim is:

1. In a device for tensioning and closing band iron hoops, the combination of a base plate having a front parallel to the band when inserted in the device, the front portion of the bottom face of the base plate being curved upward, the remainder of said face being plane, a housing erected on said base plate substantially above said curved portion, a gap between the base plate and a portion of the housing wall for the insertion of said band, a cutter head movable interiorly of and guided by said housing, a cutter mounted in said head, means for tensioning said band, and a foot-like means movably connected to said base plate, said foot-like means having one position in which it projects from the curved bottom portion of said base plate to prevent undesired tilting of said device on said curved bot-

tom portion and one position in which said device is free to tilt.

2. A device as claimed in claim 1, said foot-like means comprising a bolt movable in a direction transverse of said base front and being guided by said base plate, said bolt having a bottom face flush with the plane bottom portion of said base plate and being projectable substantially as far as the front of the latter and being retractable to clear said curved portion.

3. In a device for tensioning and closing band iron hoops, the combination of a base plate, a housing erected on said base plate, a gap between the base plate and a portion of the housing wall for the insertion of said band, a cutter head movable interiorly of and guided by said housing so as to be lowered upon and raised from said band, means for reciprocating said cutter head, a releasable detent to hold said cutter head in raised position, a tensioning roller adapted to be lowered upon and raised from said band outside said housing, a common hand-actuated element operatively connected to said detent and said tensioning roller so as to release said detent and to lower said tensioning roller, and a latch for said element to prevent its actuation, said latch embodying a movable abutment for said band so as to be shifted in unlatching position by said band upon correct insertion of the latter into said device.

4. In a device for tensioning and closing band iron hoops, the combination of a base plate having a front parallel to the band when inserted in the device, the front portion of the bottom face of said base plate being curved upward, the remainder of said face being plane, a housing erected on said base plate substantially above said curved portion, a gap between the base plate and a portion of the housing wall for the insertion of said band, a retractable foot member projectable from the curved bottom portion downward to prevent undesired tilting of the device, means for tensioning the band, a cutter head with cutter movable interiorly of and guided

by said housing, means for operating said cutter head, a releasable detent to hold said cutter head in a raised position, a reciprocatable member operative by hand, a means operatively connected to said detent and movable in the path of said reciprocatable member on one of its strokes to release said detent, and a means operatively connected to said foot member and movable in the path of said reciprocatable member on its other

stroke to withdraw said foot member from operative position.

5. A device as claimed in claim 4, further comprising a resilient member in connection with said foot member and tending to hold the latter in operative position.

6. A device as claimed in claim 4, wherein said tensioning means and said reciprocatable member includes an eccentrically hollow shaft journaled on said base plate so as to cross the direction of the band, a hand-lever secured to said shaft, a lost motion connection between said shaft and said means to release said detent, a second lost motion connection between said shaft and said means to withdraw said foot member, an inner shaft extending through said hollow shaft, a tensioning roller secured to said shaft, and a uni-directional drive for said shaft.

XAVER KUONI.
